Primary Examiner — Amber R Anderson*Assistant Examiner* — Kevin J Baynes*(74) Attorney, Agent, or Firm* — Gary Peterson(57) **ABSTRACT**

A barrier is formed from bollards and posts that are embedded in a terrain. The bollards and posts are interconnected by, and support, vertically-spaced runs of primary rails. The rails in each run are aligned in end-to-end relationship. A strengthening cable extends within each run, and is anchored at each end within a concrete-filled bollard. Each bollard contains an elongate, vertically-oriented cable entry port that can receive the end portions of all of the cables in the runs, disposed in laterally-spaced relationship. A two-part closure covers the cable entry port, and includes spaced cable openings that maintain the cables that exit the bollard at a desired lateral separation distance. A cable confinement bracket installed at each post prevents the cables from flying out of the primary rails after an impact. The bracket features a spine that restrains the cables, which pass through bays notched in the spine's lower edge. Each cable may include

attached cable clips to enhance the cable's resistance to pullout from the bollards.

CABLE-REINFORCED BARRIER

SUMMARY OF THE INVENTION

A kit is formed from a plurality of elongate cables and a plurality of elongate and hollow bollards. Each bollard has a longitudinal axis, a pair of opposed ends and an elongate axially-extending cable entry port formed intermediate those ends. The cable entry port is sized to receive the end portions of the plurality of cables therethrough while the cables are in a laterally-offset relationship.

A kit is formed from a plurality of elongate and hollow bollards, a plurality of elongate cables and a plurality of multi-part closures. Each bollard has a pair of opposed ends and a cable entry port disposed intermediate those ends. Each closure is sized to fully cover the cable entry port and has a plurality of cable openings formed therein. Each cable opening is sized to clearly receive one of the cables therethrough. Each closure is broken into parts at an internal edge that intersects each of the cable openings.

A bracket is formed from a flat and elongate spine and a plurality of longitudinally-spaced feet. The spine has an upper edge and a lower edge. The lower edge includes a plurality of longitudinally-spaced rectilinear segments, and a plurality of longitudinally-spaced bays interspersed between those segments. The feet join the lower edge of the spine at the segments, and extend in orthogonal relationship to the spine.

A kit is formed from at least one elongate and hollow bollard, a plurality of elongate cables and at least one cable placement block. The bollard has a pair of opposed ends and a cable entry port disposed intermediate its ends. The cable placement block is sized to be clearly received within the at least one bollard through its cable entry port, and has a plurality of open-topped cable channels formed therein. Each cable channel is sized to receive one of the plurality of cables therein.

BRIEF DESCRIPTION OF THE DRAWINGS

FIG. 1 is a front elevation view of a barrier situated on a terrain.

FIG. 2 is a top plan view of the barrier shown in FIG. 1, taken along line 2-2.

FIG. 3 is a side cross-sectional view of the barrier shown in FIG. 1, taken along line 3-3.

FIG. 4 is a side cross-sectional view of the barrier shown in FIG. 1, taken along line 4-4.

FIG. 5 is a perspective view of a bollard.

FIG. 6 is a side elevation view of the bollard shown in FIG. 5.

FIG. 7 is a top plan view of the bollard shown in FIG. 6, taken along line 7-7.

FIG. 8 is a front elevation view of a post.

FIG. 9 is a top plan view of the post shown in FIG. 8, taken along line 9-9.

FIG. 10 is a rear elevation view of the post shown in FIG. 9, taken along line 10-10.

FIG. 11 is a front elevation view of a rail.

FIG. 12 is a side elevation view of the rail shown in FIG. 11, taken along line 12-12.

FIG. 13 is a top plan view of the rail shown in FIG. 11, taken along line 13-13.

FIG. 14 is an enlarged front elevation view of an end portion of the rail shown in FIG. 11.

FIG. 15 is a top plan view of the end portion of the rail shown in FIG. 14.

FIG. 16 is a semi-schematic view of a strengthening cable.

FIG. 17 is a front elevation view showing the end portion of the cable shown in FIG. 16, with plural cable clips attached.

FIG. 18 is an enlarged perspective view of a cable clip.

FIG. 19 is a front elevation view of an assembled closure.

FIG. 20 is a front elevation view of the first part of the closure shown in FIG. 19.

FIG. 21 is a front elevation view of the second part of the closure shown in FIG. 19.

FIG. 22 is a perspective view of a rail attachment bracket.

FIG. 23 is a front elevation view of the rail attachment bracket shown in FIG. 22.

FIG. 24 is a side elevation view of the rail attachment bracket shown in FIG. 23, taken along line 24-24.

FIG. 25 is a front elevation view of a post plate.

FIG. 26 is a perspective view of a cable confinement bracket.

FIG. 27 is a front elevation view of the cable confinement bracket shown in FIG. 26.

FIG. 28 is a side elevation view of the cable confinement bracket shown in FIG. 27, taken along line 28-28.

FIG. 29 is a front elevation view of a panel attachment bracket.

FIG. 30 is a side elevation view of the panel attachment bracket shown in FIG. 29, taken along line 30-30.

FIG. 31 is a top plan view of the panel attachment bracket shown in FIG. 29, taken along line 31-31.

FIG. 32 is a top plan view of a portion of the barrier shown in FIGS. 1 and 2, showing the relative positioning of a bollard and two posts.

FIG. 33 shows a stage of assembly of the barrier. A post plate has been installed on the rearward flange of the post shown in FIG. 10.

FIG. 34 shows assembly of the barrier at a stage subsequent to that shown in FIG. 33. Primary rails have been attached at the post plate shown in FIG. 33.

FIG. 35 is a side elevational view of a portion of the bollard of FIG. 6, showing another stage of barrier assembly. Bundled strengthening cables, shown in cross-section, have been inserted endwise into the cable entry port of the bollard shown in FIG. 6, and the first piece of the closure installed on the bollard.

FIG. 36 is a side elevational view of a portion of the bollard of FIG. 6, showing barrier assembly at a stage subsequent to that shown in FIG. 35. The second piece of the closure has been installed on the bollard shown in FIG. 35.

FIG. 37 is a perspective exploded view showing the mode of assembly of a gasket, the rail attachment bracket, and a rail.

FIG. 38 is an enlarged side elevational view of a portion of the bollard of FIG. 6, showing barrier assembly at a stage subsequent to that shown in FIG. 36. Gaskets and rail attachment brackets have been installed on the bollard, and primary rails attached to rail attachment brackets. A cable has been inserted into each primary rail. A panel attachment bracket has been installed on the bollard.

FIG. 39 is a rear elevation view of the post of FIG. 10, showing barrier assembly at a stage subsequent to that shown in FIG. 33. Primary rails have been installed on both sides of the post plate, and cables positioned within the rails. A cable confinement bracket has been installed on the post plate.

FIG. 40 is a front elevation view showing the end portions of three of the cables shown in FIG. 16, each with plural cable clips attached.

FIG. 41 is a front elevation cross-sectional view showing the end portions of the cables of FIG. 40 in an installed configuration within a bollard.

FIG. 42 is a perspective view of a cable placement block.

FIG. 43 is a front elevation view of the cable placement block shown in FIG. 42.

FIG. 44 is a right side elevation view of the cable placement block shown in FIG. 43, taken along line 44-44.

FIG. 45 is a left side elevation view of the cable placement block shown in FIG. 43, taken along line 45-45.

FIG. 46 is a top plan view of the cable placement block shown in FIG. 43, taken along line 46-46.

FIG. 47 is a bottom plan view of the cable placement block shown in FIG. 43, taken along line 47-47.

FIG. 48 shows a panel attachment bracket attached to a bollard. A panel is attached to the panel attachment bracket.

DETAILED DESCRIPTION

A barrier 10 is formed from a plurality of bollards 12 and a plurality of posts 14 situated on a terrain 16, preferably outdoors, as shown in FIGS. 1 and 2. The bollards 12 and posts 14 are embedded in the terrain 16, and form a lineal spine 18 that separates a protected zone 20 from an unprotected zone 22. The protected zone 20 may contain one or more individuals, properties or other assets that the barrier 10 is to protect.

Preferably, the barrier 10 is formed in sections 24, with each section 24 bounded by a pair of end bollards 26. Line bollards 28 and posts 14 are arranged between the end bollards 26. Adjoining sections 24 may share the same end bollard 26.

As shown in FIGS. 3 and 4, the barrier 10 includes a primary structure 30, situated nearest the protected zone 20, and a secondary structure 32, situated nearest the unprotected zone 22. Both the primary and secondary structures 30 and 32 are supported by the spine 18. The primary structure 30 protects the zone 20 from such threats as vehicular intrusion and impact, while the secondary structure 32 protects the zone 20 from more traditional threats, such as footbound intruders.

The primary structure 30 is formed from one or more runs 34 of a plurality of primary rails 36. The primary rails 36 are channel-shaped, and arranged in end-to-end relationship. A strengthening cable 38, shown in FIG. 16, extends within each run 34, and is anchored within a bollard 12 at each end.

The secondary structure 32 is formed from a plurality of secondary rails 40 and a plurality of pickets 42. The secondary rails 40, which also are channel-shaped, are assembled with the pickets 42 to form a plurality of framework panels 44. One such panel 44 is supported between each adjacent pair of posts 14, and between each bollard 12 and its adjacent post 14.

The bollard 12, shown in detail in FIGS. 5-7, is an elongate and hollow tubular member having a longitudinal axis 46 and opposed upper and lower ends 48 and 50. Preferably, each of the ends 48 and 50 is open to the bollard interior. The bollard 12 has a uniform cross-sectional shape along its length. Preferably, that cross-sectional shape is polygonal, more preferably rectangular and most preferably square. When the cross-sectional shape of the bollard 12 is rectangular, the bollard 12 is characterized by two pairs of spaced, parallel and opposed sides 52. The sides 52 include at least one front side 54 and at least one cable entry side 56.

Each cable entry side 56 is provided with an elongate axially-extending cable entry port 58 situated intermediate the ends 48 and 50. Preferably, the cable entry port 58 is

slot-like, and situated nearest to the upper end 48. The shape of the cable entry port 58 is preferably a non-square rectangle having major sides that extend parallel to the longitudinal axis 46. The cable entry port 58 is preferably situated in a laterally offset relationship to the longitudinal centerline of the cable entry side 56.

Each cable entry port 58 is preferably sized to receive the end portions of a plurality of cables 38, while those end portions are in a laterally-offset relationship. More preferably, the plurality of cables 38 have a number equaling the number of cables 38 included in a section 24 of the barrier 10.

When a bollard 12 is to serve as an end bollard 26 for the barrier 10, preferably that bollard 12 has only a single cable entry side 56. When a bollard 12 is not to serve as an end bollard 26, it preferably has two cable entry sides 56, with a single cable entry port 58 being formed in each of two sides 56. When a bollard 12 with two cable entry sides 56 is to serve as a line bollard 28, the cable entry sides 56 are spaced, parallel, and opposed, with the cable entry ports 58 situated nearest the same single side 52. When a bollard 12 with two cable entry sides 56 is to serve as a corner bollard, the cable entry sides 56 are adjacent, with the cable entry ports 58 situated nearest the shared corner of the cable entry sides 56. In all bollards 12 having two cable entry sides 56, those cable entry sides 56 are mirror images of one another.

Each cable entry side 56 is provided with a plurality of closure attachment openings 60 arrayed around the cable entry port 58. The closure attachment openings 60 are preferably identically sized and shaped. In the embodiment shown in the Figures, six closure attachment openings 60 are provided.

Each cable entry side 56 is preferably further provided with a plurality of block attachment openings 61. Preferably, the block attachment openings 61 are situated at axially opposed ends of the cable entry port 58, and are identically sized and shaped. In the embodiment shown in the Figures, two block attachment openings 61 are provided, one adjacent each axial end of the cable entry port 58.

Each cable entry side 56 is also preferably provided with a plurality of longitudinally-spaced panel attachment openings 62 that extend along the edge that joins the front side 54. The panel attachment openings 62 preferably extend rectilinearly, with uniform spacing, and are situated nearest the upper end 48. The panel attachment openings 62 are preferably identically sized and shaped.

Each front side 54 of the bollard 12 is a substantially solid structure with no cable entry port formed in it. A bollard 12 may have one or two front sides 54. In the case of a corner bollard, the bollard 12 will have front sides 54 that adjoin one another. Other types of bollards 12 will have a single front side 54 that adjoins either or both of the cable entry sides 56 of that bollard 12.

Apart from ports and openings possibly formed in the cable entry sides 56 as described above, the bollards 12 forming the barrier 10 are preferably of identical size, shape and construction.

In one embodiment, the bollard 12 has a length of 159 inches and the cross-sectional shape of a square with sides of 10 inches. The cable entry port 58 has a rectangular shape with a major side of 14.5 inches and a minor side of 6 inches. The upper end of the cable entry port 58 is situated 39.5 inches from the upper end 48.

Two pairs of closure attachment openings 60 are respectively situated 37.81 inches and 55.19 inches from the upper end 64. A third pair of closure attachment openings 60 is situated intermediate these two pairs. The separation dis-

tance between paired closure attachment openings **60** is 3.5 inches. The two block attachment openings **61** are respectively situated 35.31 inches and 57.69 inches from the upper end **64**. The panel attachment openings **62** extend to a distance of 81.94 inches from the upper end **48** and have a 5.88-inch separation.

The post **14** is shown in detail in FIGS. 8-10. The post **14** is an elongate structure, preferably of uniform cross-sectional shape, having an upper end **64** and an opposed lower end **66**. The post **14** features a flat and elongate web **68** having a pair of laterally spaced edges. A flat and elongate flange joins each lateral edge of the web **68**, and extends in orthogonal relationship to the web **68**. The pair of opposed flanges, designated as forward flange **70** and rearward flange **72**, cooperate with the web **68** to form the I-shaped cross-sectional shape shown in FIG. 9. Preferably the post **14** has maximum cross-sectional dimensions that are less than those of the bollard **12**.

The web **68** and flanges **70** and **72** preferably comprise regions of the same single piece of material. Each flange is separated from the adjacent web **68** by a fold in the material. Each of the flanges **70** and **72** is characterized by a substantially flat double-wall structure, while the flat web **68** is a single-walled structure. The double walls of the flanges are preferably formed by folding planar portions of material into an overlapping and abutting configuration.

As shown in FIG. 8, a series of longitudinally-spaced pairs of panel attachment openings **74** are formed in the forward flange **70**, beginning nearest the upper end **64**. Preferably, respective members of each pair of openings **74** overlie opposite sides of the web **68**, and are situated at equal distance from the upper end **64**. The number of pairs of openings **74** should equal the number of secondary rails **40** in each panel **44** forming the secondary structure **32**. In the embodiment shown in the Figures, each panel includes three such rails, so the number of pairs of openings **74** is three, for a total of six panel attachment openings **74**.

The panel attachment openings **74** preferably have identical sizes and shapes. More preferably, the shape of each panel attachment opening **74** is oblong, with its major axis extending orthogonally to the longitudinal axis of the post **14**.

As shown in FIG. 10, a series of longitudinally-spaced pairs of plate attachment openings **76** is formed in the rearward flange **72**, beginning nearest the upper end **64**. Preferably, respective members of each pair of openings **76** overlie opposite sides of the web **68**, and are situated at equal distances from the upper end **64**. The number of pairs of openings **76** preferably equals two, for a total of four plate attachment openings **76**. In another embodiment, not shown in the Figures, the number of pairs of plate attachment openings equal the number of cables in a section. In such an embodiment, if a section includes three cables, the number of plate attachment openings would be six.

The plate attachment openings **76** preferably have identical sizes and shapes. More preferably, the shape of each plate attachment opening **76** is oblong, with its major axis extending parallel to the longitudinal axis of the post **14**.

Posts suitable for use in the barrier **10** are described in further detail in U.S. Pat. No. 8,382,070, the entire disclosure of which is incorporated by reference.

The posts **14** forming the barrier **10** are preferably of identical size, shape and construction. In the same embodiment described with reference to the bollard **12**, each post **14** has a length of 120 inches, a web **68** with a width of 3.88 inches, and flanges **70** and **72** with widths of 2.75 inches. The three pairs of panel attachment openings **74** are respec-

tively situated 3 inches, 15 inches and 72 inches from the upper end **64**. The two pairs of plate attachment openings **76** are respectively situated 38.5 inches and 45.5 inches from the upper end **64**.

A rail **78**, suitable for use as both a primary rail and a secondary rail in the barrier **10**, is shown in detail in FIGS. 11-15. Each rail **78** is an elongate channel-shaped member having a pair of opposed end portions **80**. A rail channel **82**, sized to receive one or more cables, runs the length of the rail **78**. The elongate opening **84** of the channel **82** in each rail **78** is situated opposite an elongate flat section **86**. A fastener opening **88** is formed at each end portion **80** of the rail **78**.

Further detail about the rail **78**, and how it is assembled with a post **14**, is provided in the aforementioned U.S. Pat. No. 8,382,070.

Preferably, the rails serving as primary rails **36** are of identical size, shape and construction. Likewise, the rails serving as secondary rails **40** are of identical size, shape and construction. The primary and secondary rails **36** and **40** are substantially identical as well. A secondary rail **40** may be provided with a series of longitudinally-spaced fastener openings in the flat section **86**, for attachment of pickets **42**, while such openings need not be provided in a primary rail **36**.

In the same embodiment described with reference to the bollard **12** and post **14**, each of the primary and secondary rails is a rail **78** with a length of 92.56 inches, a maximum height of 2.11 inches and a maximum width of 2.11 inches.

A picket **42** is shown in FIG. 3, and another in FIG. 4. Each picket **42** is supported by the secondary rails **40** forming the secondary structure **32**. A plurality of fasteners are used to secure each picket **42** to its supporting secondary rails **40**. Suitable pickets for use in the barrier **10** are described in U.S. Pat. No. 6,874,767, the entire disclosure of which is incorporated by reference. Further detail about how the picket **34** is assembled with a rail **78** is provided in the aforementioned U.S. Pat. No. 8,382,070.

The pickets **42** forming the barrier **10** are preferably of identical size, shape and construction. In the same embodiment described with reference to the bollards **12** and posts **14**, the picket **42** has a length of 94 inches and an overall width of 2.75 inches. The center-to center separation distance between adjacent pickets **34** installed on a secondary rail **40** is preferably 6 inches.

The strengthening cable **38**, shown in FIG. 16, is an elongate and flexible structure having a medial portion **90** that joins opposed end portions **92**. Each end portion **92** terminates in a free end **94**. The cable shown in the Figure has been bent to the configuration it will eventually assume in a section **24** of the barrier **10**, with a medial portion **90** extending horizontally, and end portions **92** extending vertically. When a section **24** of the barrier **10** is fully assembled, the medial portion **90** will be contained within a run **34** of primary rails **36**, and each end portion **90** will be contained within a bollard **12**.

The cables **38** forming the barrier **10** are preferably of identical size, shape and construction. In the same embodiment described with reference to the bollards **12** and posts **14**, each of the cables **38** is a steel wire rope of the 6x37 class, with a diameter of 1.25 inches and a length of 53 feet, 4 inches. In another embodiment, each cable **38** may be formed from structural strand.

A plurality of cable clips **96**, one of which is shown in FIG. 18, are preferably installed on each end portion **92** of each cable **38** forming the barrier **10**. The installed cable clips **96**, shown in FIGS. 17 and 41, are longitudinally

spaced from each other, and from the end 94 which they adjoin. The cable clips 96 increase the effective cross-sectional shape of the cable 38, and enhance the cable's resistance to pullout upon an impact to the barrier 10.

As shown in FIG. 17, the cable clips 96 in each end portion 92 are preferably arranged in first and second groups 97 and 99. Cable clips 96 in the first group 97 are installed nearest the end 94 of the end portion 92, and are preferably three in number and uniformly spaced. After the barrier 10 is assembled, cable clips 96 of the first group 97 will be situated below ground level, within the bollard 12, and no more than five feet from its lower end 50, as shown in FIG. 41. Each pair of adjacent clips 96 in the first group 97 is spaced by about one foot.

Cable clips 96 in the second group 99 are installed between the first group 97 and the medial portion 90 of the cable 38, and are preferably one in number. After the barrier 10 is assembled, cable clips 96 of the second group 99 will be situated above ground level, within the bollard 12, and approximately two to three feet below the cable entry port 58.

Some commercially-available cable clips are designed to join two cables, and may form a less-than-satisfactory connection when attached to a single cable in isolation. Such a clip is preferably installed by joining a cable 38 to another accessible cable 38 forming the barrier 10. If another cable 38 is unavailable or inaccessible, a cable clip 96 may be installed by joining a single cable 38 to a flat cable spacer (not shown) having the general shape of a cartoon dog bone.

The efficacy of the barrier 10 depends in part on the number of clips 96 attached to each cable 38 forming the barrier 10. As to each such cable 38, an attached clip 96 that is shared with a different cable 38 should be counted for only half the value of an independent clip.

When a group of cable end portions 92 is to be bundled for installation into the same bollard 12, the longitudinal positions of the clips 96 in the respective cables is preferably staggered, as shown in FIG. 40, in order to facilitate installation through the cable entry port 58. To further facilitate such installation in the circumstance when three or more cables are to be installed in a bollard 12, the clip 96 on at least one cable 38 is also preferably inverted in relation to its counterpart clips 96 on the other cables 38, as also shown in FIG. 40.

The cable clips 96 forming the barrier 10 are preferably of identical size, shape and construction. A cable clip suitable for forming the barrier 10 is the Crosby G-450 forged wire rope clip, manufactured by The Crosby Group LLC, of Tulsa, Oklahoma. The general structure of an acceptable clip is shown in U.S. Pat. No. 388,840. In the same embodiment described with reference to the bollards 12 and posts 14, the clip 96 is sized to fit a cable having a diameter of 1.25 inches.

When the end portions 92 of the cables 38 include attached cable clips 96, each cable entry port 58 is preferably sized to receive therethrough, not just the end portions 92 but the attached clips 96 as well, while the end portions 92 are in a laterally-offset relationship. More preferably, the plurality of cables 38 have a number equaling the number of cables 38 included in a section 24 of the barrier 10.

A closure 98, shown in FIG. 19, covers the cable entry port 58 of a bollard 12. Each closure 98 is formed from multiple interlocking parts, preferably two in number. The first part 100 is shown in FIG. 20, and the second part 102 is shown in FIG. 21. The closures 98 forming the barrier 10 are preferably of identical size, shape and construction.

The assembled closure 98 is a flat structure that is sized to fully cover the cable entry port 58 of a bollard 12. Each closure 98 preferably has a non-square rectangular shape bounded by parallel major external edges 104 and parallel minor external edges 106. The major external edges 104 preferably extend in parallel relationship to the longitudinal axis 46 of the bollard 12.

At least one, and preferably a plurality of cable openings 108 are formed within in the closure 98, away from the external edges 104 and 106. Each cable opening 108 is sized and shaped to closely but clearly receive a single cable 38. Preferably, each cable opening 108 is circular in shape. The number of cable openings 108 should equal the number of cables 38 in a section 24 of the barrier 10. In the embodiment shown in the Figures, there are three such cables 38 in a section 24, so the number of cable openings 108 in the closure 98 should be three as well.

When the closure 98 is provided with plural cable openings 108, those openings should be aligned along a line that parallels the major external edges 104 of the closure 98. The spacing between adjacent cable openings 108 should match the desired vertical spacing between cables 38 in a section 24 of the barrier 10.

The closure 98 is broken into first and second parts 100 and 102 by an internal edge 110, which extends between the minor external edges 106 and intersects each of the cable openings 108. Preferably, the first part 100 includes a plurality of concave cable support segments 112, equal in number to the number of cable openings 108. Each cable support segment 112 constitutes a major portion of the periphery of a corresponding cable opening 108.

A plurality of bracket attachment openings 114 are formed in the closure 98. Preferably, the bracket attachment openings 114 are formed in only one of the two parts of the closure 98. Thus, in the embodiment shown in the Figures, bracket attachment openings 114 are formed in the second part 102, and not in the first part 100.

The part of the closure 98 within which the openings 114 are formed should be situated nearest the unprotected zone 22. In the embodiment shown in the Figures, the number of bracket attachment openings 114 in the closure 98 is six, with two openings 114 formed above and below each cable opening 108.

In another embodiment, not shown in the Figures, bracket openings are formed in both sides of the closure, so that each cable opening is surrounded by four such openings. Such a configuration may be useful in an embodiment in which plural rail attachment brackets, rather than a single such bracket, are installed at each bollard.

At least one, and preferably of plurality of pairs of bollard attachment openings 116 are formed in the closure 98, away from the external edges 104 and 106. Each bollard attachment opening 116 is preferably elongate and slotlike. One member of each pair of bollard attachment openings 116 is situated adjacent each major external edge 104. The paired bollard attachment openings 116 are preferably of identical size and shape, and are situated at equal distances from the same minor external edge 106.

When plural pairs of bollard attachment openings 116 are provided, the bollard attachment openings 116 adjacent each major external edge 104 are longitudinally spaced and collinear. In the embodiment shown in the Figures, the number of pairs of bollard attachment openings 116 is three, for a total of six bollard attachment openings 116.

The closures 98 forming the barrier 10 are preferably of identical size, shape and construction. In the same embodiment described with reference to the bollards 12 and posts

14, the closure 98 has a rectangular shape with a major side of 20 inches and a minor side of 6.35 inches. The cable openings 108 are circular, and have a diameter of 1.25 inches. Adjacent cable openings 108 are spaced by a center-to center separation distance of 3.5 inches.

A rail attachment bracket 118, shown in FIGS. 22-24, comprises a flat and elongate spine 120 joined to a flat base 122. Preferably the spine 120 and the base 122 are disposed in orthogonal relationship. The spine 120 and base 122 may be formed from a single piece of material, or may be formed from two or more pieces that are joined by welding or fasteners.

The base 122 is characterized by spaced and opposed first and second edges 124 and 125. The spine 120 is joined to the base 122 intermediate the edges 124 and 125. A series of longitudinally-spaced closure attachment openings 126 is formed in the base 122 adjacent the first edge 124. The closure attachment openings 126 are arranged in a pattern that registers with the pattern of bracket attachment openings 114 in the closure 98.

At the second edge 125, which is situated on the opposite side of the spine 120 from the closure attachment openings 126, a series of longitudinally-spaced bays 128 is formed in the base 122. Preferably, the bays 128 have identical sizes and shapes. Each bay 128 is sized to receive a cable 38 therethrough. The bays 128 are provided in a number that equals the number of cables 38 in a section 24 of the barrier 10. In the embodiment shown in the Figures, there are three such cables 38, so the number of bays 128 is three.

A series of longitudinally-spaced rail attachment openings 130 is formed in the spine 120. The openings 130 are provided in a number that equals the number of cables 38 in a section 24 of the barrier 10. In the embodiment shown in the Figures, there are three such cables 38, so the number of openings 130 is three. Each rail attachment opening 130 is situated adjacent a corresponding one of the bays 128.

The rail attachment brackets 118 forming the barrier 10 are preferably of identical size, shape and construction. In the same embodiment described with reference to the bollards 12 and posts 14, the rail attachment bracket 118 features a base 122 of generally trapezoidal shape, with the first edge 124 being its major side. The length of the first edge 124 is 12 inches. The spine 120 has a rectangular shape with a major side of 12 inches and a minor side of 1.75 inches. Each bay 128 is 1.5 inches wide and 2.13 inches deep.

In another embodiment, not shown in the Figures, each rail attachment bracket 118 may be replaced by a plurality of such brackets, provided in a number equal to the number of cables 38 in a section 24 of the barrier 10. Each such bracket includes a spine and a base, preferably orthogonal, but the base includes only a single bay or channel, and the spine includes only a single rail attachment opening. Plural rail attachment openings, preferably four in number, are formed in the base. The pattern of these rail attachment openings registers with the pattern of bracket attachment openings formed in the closure around each cable opening.

A post plate 132, shown in FIG. 25, is a flat and elongate structure having a pair of elongate and sinuous major edges 134. Preferably the two major edges 134 are mirror images of one another, with each edge 134 having rectilinear portions extending in parallel relationship to corresponding rectilinear portions of the other edge 134. Various openings are formed in the post plate 132, including rail attachment openings 136, bracket attachment openings 138 and post attachment openings 140.

Pairs of rail attachment openings 136 are preferably formed near the major edges 134 of the post plate 132, with one member of each pair situated adjacent each major edge 134. The pairs are provided in a number that equals the number of cables 38 in a section 24 of the barrier 10. In the embodiment shown in the Figures, there are three cables 38, so the number of pairs of rail attachment openings 136 is three, for a total of six rail attachment openings 136. The rail attachment openings 136 preferably have identical sizes and shapes. The separation distance between adjacent pairs of rail attachment openings 136 should equal the separation distance between adjacent primary rails 36 in the primary structure 30.

Pairs of bracket attachment openings 138 are likewise preferably formed near the major edges 134 of the post plate 132, with one member of each pair situated adjacent each major edge 134. In the embodiment shown in the Figures, the bracket attachment openings 138 are six in number, and are arranged in two parallel lines. The bracket attachment openings 138 preferably have identical sizes and shapes.

Preferably, each bracket attachment opening 138 is overlaid by an aligned and internally threaded nut 139, which facilitates installation of fasteners that join the cable confinement bracket to the post plate 132. Preferably each nut 139 is permanently joined to the post plate 132 by welding.

The post attachment openings 140 are preferably situated inside the array of rail attachment openings 136 and bracket attachment openings 138, and are provided in a number that matches the number of plate attachment openings 76. The post attachment openings 140 are arranged in a pattern that registers with that of the plate attachment openings 76. The post attachment openings 140 preferably have identical sizes and shapes.

The post plates 132 forming the barrier 10 are preferably of identical size, shape and construction. In the same embodiment described with reference to the bollards 12 and posts 14, the post plate 132 has a hexagonal shape with a length of 17.5 inches and a maximum width of 5.88 inches.

A cable confinement bracket 142, shown in FIGS. 26-28, comprises a flat and elongate spine 144 and a plurality of longitudinally-spaced feet 146. The spine 144 is characterized by opposed ends 148 and a pair of opposed sides 150. The ends 148 are joined by an upper edge 152 and a lower edge 154. Preferably, the edges 152 and 154 converge, without necessarily joining, adjacent each of the ends 148.

The lower edge 154 is made up of a plurality of longitudinally-spaced rectilinear segments 156 disposed in collinear relationship. Interspersed between the segments 156 are a series of longitudinally-spaced bays 158, with one bay 158 situated between each adjacent pair of segments 156.

Preferably, the bays 158 have identical sizes and shapes. Each bay 158 is sized to receive a cable 38 therethrough. The bays 158 are provided in a number that equals the number of cables 38 in a section 24 of the barrier 10. In the embodiment shown in the Figures, there are three such cables 38, so the number of bays 158 is three. Preferably, no bays are formed in the upper edge 152.

The feet 146 join the lower edge 154 of the spine 144 at the segments 156, preferably such that a one-to-one relationship exists between feet 146 and segments 156. Preferably, each foot 146 is flat and extends on both sides of the spine 144, in orthogonal relationship to the spine 144.

A pair of plate attachment openings 160 are formed in each foot 146, with one situated on each side of the spine 144. Preferably, the plate attachment openings 160 are of identical size and shape. The pattern of plate attachment

11

openings 160 should register with the pattern of bracket attachment openings 138 in the post plate 132.

The cable confinement brackets 142 forming the barrier 10 are preferably of identical size, shape and construction. In the same embodiment described with reference to the bollards 12 and posts 14, the cable confinement bracket 142 has a length of 17.5 inches, a height of 2.69 inches, and a maximum width of 5.88 inches. Each of the bays 158 has a rectangular shape with dimensions of 1.5 inches by 1.56 inches. Adjacent bays 158 have a center-to-center separation distance of 3.5 inches.

A panel attachment bracket 162, shown in FIGS. 29-31, is an elongate structure formed from a first leg 164 and a second leg 166. Each of the legs 164 and 166 is flat, and has opposed ends 168. The legs 164 and 166 are joined at a shared longitudinal edge, and are disposed in orthogonal relationship. A series of longitudinally-spaced slots 170 is formed in each of the legs 164 and 166, in spaced relationship to the ends 168.

The panel attachment brackets 162 forming the barrier 10 are preferably of identical size, shape and construction. In the same embodiment described with reference to the bollards 12 and posts 14, each panel attachment bracket 162 is 82.5 inches in length, and each of the legs 164 and 166 is 1.5 inches wide. Each slot is between 4 and 5 inches in length, with a separation distance of about 1 inch between adjacent pairs of slots 170. The slots 170 come no closer to each of the ends 168 than between about 0.5 and 1.0 inches.

FIGS. 42-47 show a cable placement block 190, which is sized and shaped to be received within the bollard 12 by way of its cable entry port 58. The cable placement block 190 functions to maintain separation of the cables 38 forming the barrier 10, even as those cables 38 come under high tension as the result of high-velocity impacts to the barrier 10. The block 190 also helps to reduce bollard-cable pinching that might threaten the barrier's structural integrity.

The cable placement block 190 is a solid wedge-like structure characterized by an enlarged base 192 that supports an elongate tower 194. The lower axial extremity 196 of the cable placement block 190 is at the base 192, and the upper axial extremity 198 at the tower 194. Preferably, the base 192 and the tower 194 are formed from a single piece of material.

The cable placement block 190 is bounded in part by a pair of flat and parallel faces 200. At one of its sides, the block 190 tapers to an edge 202 that joins the faces 200 and traverses both the base 192 and the tower 194. Formed in the tower 194 opposite the edge 202 are a plurality of axially-spaced and open-topped cable channels 204. Preferably, the number of cable channels 204 equals the number of cables 38 in a section 24 of the barrier 10. In the embodiment shown in the Figures, three cable channels 204 are provided. Each channel 204 is sized to receive a corresponding one of the cables 38.

The uppermost cable channels 204, of which there are two in the embodiment of the Figures, are preferably identical in size and shape. These uppermost channels are generally U-shaped and sized to closely conform to the cable 38 that each receives. The lowermost cable channel 204, designated by reference numeral 206, is situated nearest the base 192 and the lower axial extremity 196. The lowermost cable channel 206 is sized and shaped differently than the other cable channels 204, with a flat-bottomed shape and a side-to-side width greater than that of at least one, and preferably all, of the remaining cable channels 204 of the plurality.

The size and shape of the channel 206, which receives the lowermost cable 38 of a section 24, permit a greater range

12

of vertical cable motion than do the channels 204. When the barrier 10 experiences a heavy impact, the lowermost cable 38 will typically undergo loading before the other cables 38. The enlarged channel 206 effectively affords breathing space for the lowermost cable, so that it does not fully extend until the other cables 38 have begun to share the impact load. The risk of rupture of the lowermost cable is thereby reduced.

A plurality of bollard linkage openings 208 is provided in one of the flat faces 200 of the cable placement block 190. Two such openings 208 are provided in the embodiment shown in the Figures. The pattern of the bollard linkage openings 208 should register with the pattern of the block attachment openings in the bollard 12.

Two cable placement blocks 190 form each section 24 of the barrier, with one being installed in each bollard 12. These cable placement blocks 190 are mirror images of one another, but are otherwise of identical size, shape and construction.

In the same embodiment described with reference to the bollard 12 and post 14, the cable placement block 190 has a maximum width of 5.63 inches, a maximum height of 25 inches and a thickness of 1.5 inches. Each of the two uppermost cable channels 204 has a side-to-side width of 1.5 inches. The lowermost cable channel 206 has a flat base 3 inches in width. The side-to-side width of the channel 206 exceeds 3 inches.

Components of the barrier 10, including bollards 12, posts 14, pickets 42, rails 78, closures 98, rail attachment brackets 118, post plates 132, cable confinement brackets 142, panel attachment brackets 162 and cable placement blocks 190, are preferably formed from a strong and durable material, such as steel. To enhance its resistance to corrosion, that steel is preferably galvanized. After forming of a component is complete, a polyester powder coating is preferably applied, in order to further enhance the component's resistance to corrosion.

Assembly of the barrier 10 begins by arranging the bollards 12 and posts 14 that will form the spine 18, and embedding them into the terrain 16. Steps at this stage may be carried out for the bollards 12 and posts 14 of a single section 24, or for those of multiple sections 24.

Preferably, each of the bollard 12 and posts 14 is embedded into a corresponding underground footing, which is preferably formed from a ballast material such as concrete. Each bollard 12 and post 14 preferably extends to the base of the footing into which it is embedded.

More preferably, each bollard 12 is embedded into a footing 172, and each post 14 is embedded into a footing 174, as shown in FIGS. 1-4. The footings 172, which are preferably identical to one another, are also preferably larger and more massive, and extend more deeply, than the footings 174. Also preferably, each of the footings 172 is reinforced by a rebar cage. The footings 174 are likewise preferably identical to one another.

A bollard 12 or post 14 is embedded into a footing preferably by first digging an appropriately-sized hole in the terrain 16. The bollard or post is lowered into the hole, lower end first, and oriented vertically. If the footing is to contain any reinforcing structure, such as rebar, that structure is placed in the hole as well. Unused space within the hole is then filled with a fluid filler material, such as 4,000 psi concrete. The filler material is allowed to harden, thereby forming the footing.

Preferably, the bollards 12 are set in their respective footings 172 during an initial stage of assembly of the barrier 10. Optionally, setting of a bollard 12 into a footing 172 may

be postponed until the that bollard is to be filled with ballast material, in which case the two steps proceed concurrently.

In the same embodiment described with reference to the bollards 12 and posts 14, each footing 172 is a concrete cylinder with a depth of six feet and a diameter of three feet. Each footing 174 is a concrete cylinder with a depth of three feet and a diameter of one foot. When installed in its footing 172, each bollard 12 has an above-ground height of 7 feet, 3 inches. When installed in its footing 174, each post 14 has an above-ground height of 7 feet. The middle plate attachment openings 76 are situated 42 inches above the terrain 16.

Preferably, an adjacent pair of bollards 12 forming the barrier 10 are separated by a distance equal to the length of the cable 38, less the lengths of the two cable end portions 92 that will reside within the bollards 12. In the same embodiment described with reference to the bollards 12 and posts 14, in which the cable 38 has a length of 53 feet, 4 inches, the center-to-center separation distance between adjacent bollards 12 is 32 feet, 10 inches.

At least one, and preferably a plurality of posts 14 are situated between each adjacent pair of bollards 12 forming the barrier 10. In the embodiment shown in the Figures, the number of posts 14 between each adjacent pair of bollards 12 is three.

In the same embodiment described with reference to the bollards 12 and posts 14, the center-to-center separation distance between adjacent posts 14 is 96 inches. In the same embodiment, for those posts 14 situated nearest to a bollard 12 on one side, the center-to-center bollard-post separation distance is 110 inches.

In each section 24 of the barrier 10 in which the spine 18 is rectilinear, the bollards 12 and posts 14 should be collinear, as shown in FIG. 32. The posts 14 should be arranged so that their forward flanges 70 face the unprotected zone 22. Each bollard 12 should be arranged such that one of its front sides 54 faces the unprotected zone 22, and one of its cable entry sides 56 faces in the direction that the cable 38 will extend. The front side 54 of the bollard 12 and the forward flanges 70 of the post 14 should extend within the same single plane 176. The cable entry sides 56 of the end bollards 26 should face one another.

In a subsequent stage of assembly, the primary structure 30 of the barrier 10 is attached to the spine 18. Although it is preferred to first attach the primary structure 30 and to thereafter attach the secondary structure 32, this order of installation may be reversed. Further, installation steps relating to the secondary structure 32 may be interspersed with, or proceed concurrently with, steps relating to the primary structure 30.

At an initial stage of assembly of the primary structure 30, post plates 132 are installed on the rearward flanges 72 of posts 14. Steps at this stage may be carried out for the posts 14 of a single section 24, or for posts 14 in multiple sections 24. To install a post plate 132, the post attachment openings 140 are aligned with the plate attachment openings 76. Fasteners are inserted through the aligned openings and actuated to complete the attachment. The resulting structure is shown in FIG. 33. These steps are repeated for each post 14 in a section 24 under assembly.

At a subsequent stage of assembly of the primary structure 30, primary rails 36 are installed between adjacent pairs of posts 14. A primary rail 36 is first arranged so that its opening 84 faces toward the protected zone 20. Each end portion 80 of the primary rail 36 is positioned in overlying relationship to the post plate 132 of a corresponding post 14. The fastener opening 88 is aligned with a rail attachment opening 136, chosen so that the primary rail 36 extends

substantially horizontally. Fasteners are inserted through the aligned openings and actuated to complete the attachment. The resulting structure is shown in FIG. 34. These steps are repeated for each primary rail 36 in a section 24 under assembly.

Installation of those primary rails 36 that interconnect a post 14 with a bollard 12 are preferably postponed to a later stage of assembly, to be described hereafter.

In a subsequent stage of assembly of the primary structure 10, cables 38 are bundled together and installed into bollards 12. Steps at this stage may be carried out for the bollards 12 and cables 38 of a single section 24, or for the bollards 12 and cables 38 of multiple sections 24.

If not done previously, clips 96 are installed at each end 15 of each cable 38 that will form a section 24, as shown and described with reference to FIGS. 17 and 40. The cables 38 are laid out, preferably on the terrain 16, such that their opposite ends 94 are positioned adjacent the bollards 12 in which they are to be installed. FIGS. 17 and 40 show how the end portions 92 of the cables 38, with attached clips 96, are to be arrayed adjacent each bollard 12.

The end portions 92 of the cables 38 are next temporarily bundled together with a pair of ligatures (not shown). These ligatures are preferably applied to the cables 38 on opposite 25 sides of the plurality of clips 96, and may be formed from adhesive tape or flexible cord. The bundled end portions 92 are next inserted into the cable entry port 58 of the adjacent bollard 12.

After each ligature of the bundle enters the bollard 12, that 30 ligature is preferably released, as by cutting. Once inside a bollard 12, the cables 38 are pushed until their ends 94 are situated adjacent the lower end 50. After insertion of the cables 38 and release of the ligatures, the end portions 92 of the cables 38 should be positioned as shown in FIG. 41.

The cable placement block 190 is next installed by 35 inserting it into the bollard 12 at the cable entry port 58. Within the bollard 12, the cable placement block 190 is manipulated such that its edge 202 faces the protected zone 20, and such that a face 200 engages the cable entry side 56 of the bollard 12. The bollard linkage openings 208 in the face 200 are aligned with the block attachment openings 61 in the bollard 12. Fasteners 210, one of which is shown in FIG. 38, are inserted through the aligned openings and actuated to complete the attachment.

The first part 100 of the closure 98 is next positioned on the cable entry side 56 of a bollard 12, in partially overlying relationship to the cable entry port 58. Each of the cables 38 exiting the bollard 12 is rested on a corresponding one of the cable support segments 112. Bollard attachment openings 116 in the first part 100 are aligned with closure attachment openings 60 in the bollard 12, fasteners 178 are inserted into the aligned openings, and the fasteners 178 actuated to attach the first part 100 to the bollard 12. The resulting structure is shown in FIG. 35.

The second part 102 of the closure 98 is next positioned on the cable entry side 56 of the bollard 12, and assembled with the first part 100 to form a complete closure 98. Each of the cables 38 now exits the bollard 12 through a corresponding one of the cable openings 108. Bollard attachment openings 116 in the second part 102 are aligned with closure attachment openings 60 in the bollard 12, fasteners 178 are inserted into the aligned openings, and the fasteners 178 actuated to attach the second part 102 to the bollard 12. The cable entry port 58 is now fully closed by the closure 98. The resulting structure is shown in FIG. 36.

Once the bollard 12 has been assembled as just described, each cable opening 108 should be situated at an above-

ground height that equals the desired height of the horizontal run 34 of the cable 38 in the section 24. If necessary, the height of the cable openings 108 may be adjusted by loosening the fasteners 178 and moving the closure 98 vertically. The elongate shape of the bollard attachment openings 116 permits a significant range of vertical adjustment, and thereby relieves any need for the kind of extreme precision that might otherwise be required in placement of the bollards 12.

The foregoing steps are repeated for each bollard 12 in a section 24 under assembly. In the same embodiment described with reference to the bollards 12 and posts 14, the above-ground heights of the cable openings 108 are 38.5 inches, 42 inches, and 45.5 inches.

In a subsequent stage of assembly of the primary structure 30, rail attachment brackets 118 are installed on bollards 12. Steps at this stage may be carried out for the bollards 12 of a single section 24, or for the bollards 12 of multiple sections 24.

Each rail attachment bracket 118 is configured to join an end portion 80 of one of the primary rails 36 to one of the closures 98. A rail attachment bracket 118 is installed by positioning its base 122 against an installed closure 98, such that each bay 128 registers with a corresponding one of the cable openings 108. Optionally, an elastomeric gasket 180, shown in FIG. 37, may be sandwiched between the base 122 and the closure 98. Closure attachment openings 126 in the rail attachment bracket 118 are aligned with bracket attachment openings 114 in the closure 98 (and corresponding openings in the gasket 180, if any). Fasteners 181 are inserted through the aligned openings, and the fasteners actuated to form an attachment. These steps are repeated for each cable opening 108 in the closure 98, and for each bollard 12 in a section 24 under assembly.

Once a rail attachment bracket 118 is attached to a closure 98 adjacent a cable opening 108, each cable 38 exiting the bollard 12 passes through a corresponding one of the bays 128 of the rail attachment bracket 118. If a gasket 180 underlies the rail attachment bracket 118, a slit or opening in the gasket 180 permits passage of the cable 38 therethrough.

In a subsequent stage of assembly of the primary structure 30, primary rails 36 are installed between bollards 12 and adjoining posts 14. Steps at this stage may be carried out for the primary rails 36, bollards 12 and posts 14 of a single section 24, or for those of multiple sections 24.

The mode of joining a primary rail 36 to a bollard 12 is shown in FIG. 37. The fastener opening 88 at the end portion 80 of a primary rail 36 is aligned with a rail attachment opening 130 in the tab 122 of a rail attachment bracket 118. A fastener 182 is inserted through the aligned openings, and the fastener 182 actuated to secure the primary rail 36 to the rail attachment bracket 118, which is turn secured to the bollard 12. Installation of the other end of the primary rail 36 to a neighboring post 14 follows the same steps described with reference to FIG. 34. The foregoing steps are repeated for each primary rail 36 that will join a bollard 12, and for each bollard 12 in a section 24 under assembly.

With all of the primary rails 36 of a section 24 installed, each of the cables 38 is inserted into a corresponding one of the runs 34 of primary rail 36 in that section 24. Insertion occurs at the openings 84 of the primary rails 36. The resulting structure, viewed at bollard 12, is shown in FIG. 38. While a panel attachment bracket 162 is shown as installed in FIG. 38, the installation can be postponed until a subsequent stage of the assembly process.

In a subsequent stage of assembly of the primary structure 30, each bollard 12 is filled from its upper end 48 with a

ballast material, such as 4,000 psi concrete. If concrete is chosen as the ballast material, it is preferably poured into the bollard 12 as a fluid filler material and then allowed to harden, in the same manner described with reference to the footings 172 and 174. Ballast material should fill a bollard 12 above the level of the contained cables 38, and above the uppermost extent of the cable entry port 58.

Steps at this stage may be carried out for the bollards 12 of a single section 24, or for bollards 12 of multiple sections 24. If a bollard 12 is to receive additional cables 38 from an adjoining section 24, the filling step should be postponed until all such cables 38 have been received inside the bollard 12.

In a subsequent stage of assembly of the primary structure 30, and after each cable 38 has been installed in a run 34, cable confinement brackets 142 are installed on the posts 14. Steps at this stage may be carried out for the posts 14 of a single section 24, or for posts 14 of multiple sections 24.

To install a cable confinement bracket 142, plate attachment openings 160 are aligned with bracket attachment openings 138 in the post plate 132. Fasteners are inserted through the aligned openings and actuated to complete the attachment. The resulting structure is shown in FIG. 39. These steps are repeated for each post 14 in a section 24 under assembly.

The spine 144 of the installed bracket 142 overlies the cables 38, which pass transversely through the bays 158. The cables 38 are blocked from lateral removal at the mouths of the bays 158 by the post 14, via its attached post plate 132. Should the primary structure 30 experience an impact, the spine 144 prevents the cables 38 from flying out of openings 84 in the primary rails 36. The protection afforded by the primary structure 30 is thereby enhanced.

At an initial stage of assembly of the secondary structure 32, a panel attachment bracket 162 is attached to each bollard 12. Steps at this stage may be carried out for the bollards 12 of a single section 24, or for bollards 12 of multiple sections 24.

To install a panel attachment bracket 162, its first leg 164 is placed flush against the cable entry side 56 of the bollard 12, nearest the unprotected zone 22. The panel attachment bracket 162 should extend parallel to the longitudinal axis 46 of the bollard 12, and its second leg 166 should extend away from the bollard, in coplanar relationship to the front side 54. The elongate slots 170 in the first leg 164 are aligned with panel attachment openings 62 in the bollard 12. Fasteners 184 are inserted through the aligned openings and actuated to complete the attachment. The resulting structure is shown in FIGS. 38 and 40. These steps are repeated for each bollard 12 in a section 24 under assembly.

In a subsequent stage of assembly of the secondary structure 32, panels 44, comprising a framework of secondary rails 40 and pickets 42, are attached to the spine 18. One such panel 44 is supported between each adjacent pair of posts 14, and between each bollard 12 and any adjacent post 14. The panels 44 may be pre-assembled offsite, or assembled onsite in the course of installation of the barrier 10. Steps at this stage may be carried out for the bollards 12 and posts 14 of a single section 24, or for those of multiple sections 24.

A panel 44, or a secondary rail 40 that will form such a panel 44, is joined to a bollard 12 by orienting a secondary rail 40 such that its opening 84 (shown in FIG. 12) faces toward the protected zone 20. The end of the secondary rail 40 is positioned in underlying relationship to the second leg 166 of the panel attachment bracket 162. The fastener opening 88 of the secondary rail 40 is aligned with a slot 170

in the second leg 166. Fasteners 186 are inserted through the aligned openings and actuated to complete the attachment. The resulting structure is shown in FIG. 48. These steps are repeated at the bollard 12 for each secondary rail 40 that is either in a panel 44 or will form such a panel 44.

A panel 44, or a secondary rail 40 that will form such a panel 44, is joined to a post 14 by similar steps, with the forward flange 70 of the post 14 replacing the second leg 166 of the panel attachment bracket 162, and a panel attachment opening 74 replacing the slot 170. These steps are repeated at the post 14 for each secondary rail 40 that is either in a panel 44 and or will form such a panel 44.

When a panel 44 extends between a bollard 12 and adjacent post 14, or between two adjacent posts 14, each secondary rail 40 should extend substantially horizontally in relationship to the terrain 16, and in parallel relationship to the other secondary rails 40 in the panel 44. The slots 170 and panel attachment openings 74 where the secondary rails 40 are attached should be chosen accordingly.

The foregoing steps are repeated for each bollard 12 and each post 14 in the section 24 under assembly.

A longitudinally-spaced series of parallel pickets 42 are attached to the flat section 86 of each of the secondary rails 40. Preferably, each picket 42 extends vertically, and in orthogonal relationship to the secondary rails 40. The secondary rails 40 and pickets 42 cooperate to form the panel 44. If not part of a preassembled panel 44, the pickets 42 are preferably attached to the secondary rails 40 after those rails have been attached at their ends to their supporting posts 14 and/or bollards 12.

The foregoing steps are repeated until a panel 44 is formed or installed between each bollard 12 and adjacent post 14 of the section 24 under assembly, and between each adjacent pair of posts 14 of the section 24 under assembly.

The foregoing steps are repeated for each section 24 of the barrier 10. The barrier shown in FIGS. 1 and 2 has five such sections.

The barrier 10 may be assembled from a kit. The kit may comprise a plurality of bollards 12 and a plurality of cables 38. The kit may further include a plurality of closures 98. The kit may further include a plurality of cable clips 96.

Another kit may comprise a plurality of bollards 12, a plurality of cables 38, and a plurality of closures 98. The kit may further include a plurality of rails 78 and a plurality of rail attachment brackets 118.

Another kit may comprise a plurality of cable confinement brackets 142, a plurality of cables 38, and a plurality of posts 14.

Another kit may comprise a plurality of bollards 12, a plurality of cables 38, and a plurality of cable clips 96.

Another kit may comprise at least one, and preferably a plurality of the bollards 12, a plurality of the cables 38, and at least one, and preferably a plurality of the cable placement blocks 190.

Additional components of the barrier 10 described herein, as well as fasteners and other installation hardware, may be included in any of the kits. Components of each of these kits are preferably provided in a number sufficient to form the barrier 10, or a section 24 thereof.

Unless otherwise stated herein, any of the various parts, elements, steps and procedures that have been described should be regarded as optional, rather than as essential. Changes may be made in the construction, operation and arrangement of these parts, elements, steps and procedures without departing from the spirit and scope of the invention as described in the following claims.

The invention claimed is:

1. A system, comprising:
a terrain; and
a kit, comprising:

a plurality of elongate cables, each cable having an end portion; and

a plurality of elongate and hollow bollards, each bollard having a longitudinal axis, a pair of opposed ends and an elongate axially-extending cable entry port formed intermediate its ends, the cable entry port sized to receive the end portions of the plurality of cables therethrough while the cables are in a laterally-offset relationship;

in which one of the plurality of bollards is embedded at one of its ends within the terrain, in which the end portion of each of the plurality of cables is situated within the embedded bollard, and in which each of the plurality of cables extends through the cable entry port of the embedded bollard, the cables being in a laterally-offset relationship.

2. The system of claim 1 in which the cable entry part has a major side extending parallel to the longitudinal axis of the bollard.

3. The system of claim 1, in which the kit further comprises:

a plurality of multi-part closures, each closure sized to fully cover the cable entry port and having a plurality of cable openings formed therein, each cable opening being sized to clearly receive one of the cables therethrough, each closure being broken into parts at an internal edge that intersects each of the cable openings.

4. The system of claim 3 in which each closure is provided with plural closure openings, and in which each bollard is provided with plural closure attachment openings alignable with the plural closure openings of a closure.

5. The system of claim 3 in which each bollard is characterized by an exterior and an interior, and each closure is configured to cover the cable entry port at the bollard exterior.

6. The system of claim 1, in which the kit further comprises:

a plurality of cable clips, each cable clip attachable to the end portion of one of the cables.

7. The system of claim 6 in which the cable entry port of each bollard is sized to receive the end portions of the plurality of cables therethrough, while each end portion carries one or more attached cable clips and while the cables are in a laterally-offset relationship.

8. The system of claim 1 in which the opposed ends of each bollard are characterized as first and second ends, the cable entry port of each bollard is situated adjacent the first end, and each bollard is configured to be filled with ballast material from the second end to a level above the cable entry port.

9. The system of claim 1 in which each bollard has a polygonal cross-sectional shape.

10. The system of claim 9 in which each bollard has a square cross-sectional shape.

11. A bracket, comprising:

a flat and elongate spine having an upper edge and a lower edge, the lower edge comprising:

a plurality of longitudinally-spaced rectilinear segments; and

a plurality of longitudinally-spaced bays interspersed between the segments; and

a plurality of longitudinally-spaced feet joining the lower edge of the spine at the segments, and extending in orthogonal relationship to the spine.

19

12. The bracket of claim 11 in which the spine has a pair of opposed sides, and in which each foot extends on both sides of the spine.
13. The bracket of claim 11 in which each foot is flat.
14. The bracket of claim 11 in which no bays are formed in the upper edge of the spine.
15. A kit, comprising:
a plurality of the brackets of claim 11;
a plurality of elongate cables; and
a plurality of elongate posts, each post having opposed ends.
16. A system, comprising:
a terrain; and
the kit of claim 15, in which one of the plurality of posts is embedded at one of its ends in the terrain, in which one of the plurality of brackets is supported by the post, and in which each of the plurality of cables extends transversely through a corresponding one of the bays of the supported bracket.
17. The system of claim 16, in which the embedded post laterally blocks each bay of the bracket.
18. The kit of claim 15 in which each post is formed as a piece separate from each bracket.
19. The kit of claim 15 in which each of the plurality of cables is flexible.
20. A kit, comprising:
at least one elongate and hollow bollard, the bollard having a pair of opposed ends and a cable entry port disposed intermediate its ends;
a plurality of elongate cables; and
at least one cable placement block, the cable placement block sized to be clearly received within the at least one bollard through its cable entry port and having a plurality of open-topped cable channels formed therein, each cable channel sized to receive one of the plurality of cables therein;
21. The kit of claim 20 in which a plurality of block attachment openings are formed in the bollard, in which a plurality of bollard attachment openings are formed in the cable placement block, the pattern of block attachment openings being registrable with the pattern of bollard attachment openings.
22. A system, comprising:
a terrain; and
the kit of claim 20, in which the at least one bollard is embedded at one of its ends within the terrain, in which the at least one cable placement block is installed within said bollard, and in which each of the plurality of cables passes through the cable entry port and

20

- extends within a corresponding one of the cable channels of the cable placement block.
23. A kit, comprising:
a plurality of elongate cables, each cable having an end portion; and
a plurality of elongate and hollow bollards, each bollard having a longitudinal axis, a pair of opposed ends and an elongate axially-extending cable entry port formed intermediate its ends, the cable entry port sized to receive the end portions of the plurality of cables therethrough while the cables are in a laterally-offset relationship;
in which the opposed ends of each bollard are characterized as first and second ends, the cable entry port of each bollard is situated adjacent the first end, and each bollard is configured to be filled with ballast material from the second end to a level above the cable entry port.
24. A kit, comprising:
a plurality of elongate cables, each cable having an end portion; and
a plurality of elongate and hollow bollards, each bollard having a longitudinal axis, a pair of opposed ends and an elongate axially-extending cable entry port formed intermediate its ends, the cable entry port sized to receive the end portions of the plurality of cables therethrough while the cables are in a laterally-offset relationship;
in which each bollard has a polygonal cross-sectional shape.
25. The kit of claim 24 in which each bollard has a square cross-sectional shape.
26. A kit comprising:
a plurality of elongate cables, each cable having an end portion;
a plurality of elongate and hollow bollards, each bollard characterized by an exterior and an interior and having a longitudinal axis, a pair of opposed ends and an elongate axially-extending cable entry port formed intermediate its ends, the cable entry port sized to receive the end portions of the plurality of cables therethrough while the cables are in a laterally-offset relationship; and
a plurality of multi-part closures, each closure sized to fully cover the cable entry port and having a plurality of cable openings formed therein, each cable opening being sized to clearly receive one of the cables therethrough, each closure being broken into parts at an internal edge that intersects each of the cable openings and being configured to cover the cable entry port at the bollard exterior.
